(57) **CLAIM**

The ornamental design for a twist, turn, and pry device, as shown and described herein.

DESCRIPTION

FIG. 1 is a front elevation view of a twist, turn, and pry device;

FIG. 2 is a right side elevation view thereof;

FIG. 3 is a left side elevation view thereof;

FIG. 4 is a rear elevation view thereof;

FIG. 5 is a top plan view thereof, shown in larger scale;

FIG. 6 is a bottom plan view thereof, shown in the same larger scale as FIG. 5;

FIG. 7 is a bottom rear perspective view thereof;

FIG. 8 is a top rear perspective view thereof;

FIG. 9 is a cross sectional view through cut line 9-9 of FIG. 4;

FIG. 10 is an enlarged detail view of the encircled portion "10" of FIG. 4;

FIG. 11 is an enlarged detail view of the encircled portion "11" of FIG. 4;

FIG. 12 is an enlarged detail view of the encircled portion "12" of FIG. 4;

FIG. 13 is an enlarged detail view of the encircled portion "13" of FIG. 8; and,

FIG. 14 is an enlarged detail cross sectional view "14" of the encircled portion of FIG. 9.

The dash-dash and dotted lines in the drawings illustrate portions of the twist, turn, and pry device that form no part of the claimed design.

The circular long dash-short dash lines in FIGS. 4, 8, and 9 depict the limits of the enlarged views of the twist, turn, and pry device, and form no part of the claimed design.

1 Claim, 6 Drawing Sheets
